UNITED STATES PATENT OFFICE

JOHN H. HOLM, OF KENOSHA, WISCONSIN, ASSIGNOR TO HOLM COMPANY, OF KENOSHA, WISCONSIN, A CORPORATION OF WISCONSIN

DESIGN FOR A GOLF-TEEING STAND OR SIMILAR DEVICE

Application filed July 14, 1930. Serial No. 36,342. Term of patent 3½ years.

To all whom it may concern:

Be it known that I, JOHN H. HOLM, a citizen of the United States, residing at Kenosha, in the county of Kenosha and State of Wisconsin, have invented a new, original, and ornamental Design for a Golf-Teeing Stand or Similar Device, of which the following is a specification, reference being had to the accompanying drawings, forming part thereof, in which—

Fig. 1 is a front elevation of a golf teeing stand or similar device showing my new design, and

Fig. 2 is a side elevation of the same.

I claim:

The ornamental design for a golf teeing stand or similar device, as shown.

JOHN H. HOLM.
